CLAIM

The ornamental design of a capped electrical connection head, as shown.

DESCRIPTION

FIG. 1 is a side elevational view of a capped electrical connection head in accord with our new design, the opposite side thereof being the mirror image,

FIG. 2 is a front elevational view of our new design,

FIG. 3 is a rear elevational view of our new design,

FIG. 4 is a bottom view as taken from FIG. 1,

FIG. 5 is a top plan view as taken with respect to FIG. 1, FIG. 6 is a side elevational view of another embodiment of a capped electrical connection head in accord with our new design, the opposite side elevational view being the mirror image thereof,

FIG. 7 is a front elevational view as taken from the left of FIG. 6,

FIG. 8 is a rear elevational view as taken from the right of FIG. 6,

FIG. 9 is a bottom view of the embodiment of FIG. 6; and, FIG. 10 is a top plan view of the design of FIG. 6.
